APPARATUS FOR COMPRESSING AND EXPLODING GASEOUS FUEL MIXTURES

Harry C. Dunning, Columbus, Ohio

Original application August 3, 1950, Serial No. 177,454. Divided and this application May 14, 1952, Serial No. 287,795

6 Claims. (Cl. 60—39.53)

1

This invention relates to an improved combustion products generator, particularly a generator in which a pressure fluid is developed by the compression, burning and forced expulsion of successive charges of a combustible fuel mixture delivered to and removed from internal cylinders of the generator.

An object of the invention is to provide an improved generator for the production of products of combustion in which vaporized fuels are compressed in the cylinders of the generator by piston action, the latter being produced through application of an extraneous source of power to the generator.

Another object of the invention is to provide a combustion products generator having an operating shaft driven by an extraneous source of power, and wherein the generator around said shaft is provided with banks of fuel-compressing and burning cylinders, the latter being equipped with sliding pistons driven by said shaft.

A further object of the invention is to provide a generator of this character in which the sliding pistons are united with an associated power shaft in a manner offering thrust resistance to the movement of cylinder pistons in response to the expansive energy of fuel gases burned in said cylinders.

Additional objects of the invention are: to provide a pressure generator in which burning fuel gases are forced by piston action, and their autogenous pressure, from the cylinders of the generator through confined outlet passages, and wherein, through operation of generator-actuated pump means, water, or other readily vaporizable fluid, is injected in regulated amounts into the burning fuel gases while the latter are traveling through said passages, forming an elastic pressure fluid; to provide an automatically controlled power-generating system of the nature specified in which an internal combustion type of pressure generator is employed to establish a body of such a pressure fluid in a confined reservoir means, and to provide, generally, a power system which constitutes an improvement upon prior systems of a related character hitherto provided in the art.

For a further understanding of the invention, reference is to be had to the following description and the accompanying drawing, wherein:

Fig. 1 is a side elevational view, with parts broken away and shown in vertical section, of a combustion products generator formed in accordance with the present invention;

Fig. 2 is a vertical sectional view taken through the generator;

2

Fig. 3 is a horizontal sectional view on the plane indicated by the line 3—3 of Fig. 2;

Fig. 4 is a similar view on the line 4—4 of Fig. 2;

Fig. 5 is a diagrammatic view of the system in which the generator is employed.

This application is a division of my prior application, Serial No. 177,454, filed August 3, 1950, and entitled "Power-Generating System," now abandoned.

10 In said prior application, and as shown in Fig. 5, power-generating and utilizing systems are set forth involving a combustion products generator A by which vaporized fuel is successively drawn into, compressed and ignited in the internal cylinders of the generator. The burning gases are then forcibly expelled from the cylinders of the generator by the operation of power-driven piston means which are driven independently of and in opposition to the energy created by the burning gases. In said system, these gases, immediately upon their discharge from the generator, have intermingled therewith regulated quantities of water, or other similar readily vaporizable liquid. The latter is adapted to be 15 commingled with the gaseous burned or burning products of combustion and delivered to a pressure fluid accumulator or reservoir R. From this reservoir, the pressure fluid is withdrawn under regulated valve action and delivered to the cylinders of a radial fluid motor M to drive the power take-off shaft of the motor, means being provided for utilizing a part of this power to 20 operate the combustion products generator.

The present application is concerned particularly with the construction of the combustion products generator and the means forming a component part thereof for introducing a vaporizable liquid into the highly heated products of combustion expelled from the cylinders of the generator. The latter is also referred to hereafter 25 as a pressure-generating unit, and is indicated in its entirety by the reference character A in the drawings of this application.

As seen in Fig. 2, the pressure-generating unit 30 A, in the form of the invention illustrated, comprises a casing embodying a base section 1 which, for present purposes, will be described as being disposed in an upright or vertical position. The base section includes an upper wall 2 provided with an annularly shouldered seat shown at 3. Positioned on this seat and held against lateral displacement thereon is the annularly shouldered end 4 of an upper cylinder section 5, the latter being bolted or otherwise secured as at 6 to the base section 1.

The cylinder section includes an intermedi-

ate horizontally positioned wall 7. Also, the top of said section is formed with an opening 8 which is closed by a cover plate 9. This plate has its under surface formed contiguous to its outer periphery with an annularly shouldered seating surface 10 which projects into the opening 8 and is seated in connection with the upper wall of the cylinder section against transverse displacement, the cover plate being held in position by bolts or their equivalents 11, the threaded shanks of the latter being received within threaded openings appropriately formed in the top wall of the cylinder section.

As shown particularly in Figs. 2 and 3 of the drawings, the upper portion of the cylinder section is formed to include a plurality of radially disposed piston-receiving cylinders 12, in which are slidably mounted piston members 13 by which initial or low-stage compression is imparted to fuel mixtures. Below this upper bank of cylinders, the cylinder section is formed with a lower bank of parallel radially extending cylinders 14, each of which is preferably of a smaller diameter than any one of the complementary cylinders shown at 12, and in which cylinders 14 high-stage compression and combustion of fuel gases take place. Complementary cylinders of the upper and lower banks are united by means of diagonally extending fluid passages 15, the latter providing for the transmission of a compressed and explosive fuel charge from the cylinders of the upper bank into the cylinders of the lower bank. Piston members 16 are provided in the lower cylinders 14 and are adapted on sliding movement to further compress the initially compressed explosive fuel charges led into the cylinders 14 from the cylinders 12 by way of the passages 15. The passages 15 extend diagonally inwardly of the generator so that the bottom piston member 16 will be in a position to further compress the gaseous fuel charges when the latter enter the lower cylinders 14 prior to combustion of the finally compressed fuels in said last-named cylinders.

The piston members 13 and 16 are actuated by a vertically disposed externally driven shaft 17. The lower end of this shaft is reduced and mounted in a thrust bearing 18 provided in connection with a bottom plate 19, the latter being removably bolted as at 20 to the lower edge of the base section 1. Additionally, the upper wall 2 of the base section is formed with a bearing 21 which receives for rotation an intermediate portion of the driving shaft 17. Similarly, the intermediate wall 7 of the cylinder section is formed axially with a bearing 22 in which an intermediate portion of the drive shaft is rotatably received, and the upper end of the drive shaft is rotatably mounted in a bearing 23 provided in the removable cover plate 9. The base section 1 includes an internal lubricant-receiving chamber 24. Mounted in connection with the walls of this chamber is an externally threaded oil pump casing 25. This casing includes a longitudinally extending bore in which is mounted for reciprocation a sleeve 26, the latter having an open outer end and a closed inner end. A coil spring 27 is positioned in the sleeve 26, so that one end of the spring presses against the closed inner end of said sleeve while the other end of said spring engages with the outer end of the pump casing 25. A pipe line 28 enters the outer end of the casing 25 to conduct lubricant to various points of the apparatus employed

in the generator and other system parts requiring forced lubrication.

The closed inner end of the sleeve 26 includes a ball 29 which engages with the periphery of an eccentric 30 fixed to the lower end of the drive shaft 17, so that as the latter is rotated, the fluid-displacing sleeve 26 of the oil pump will be reciprocated first in one direction by the action of the eccentric 30 and then in the other by the action of the spring 27. An inlet port 31 formed in the sleeve 26 registers with a similar port 32 provided in the casing 25 when the sleeve 26 occupies its fullest inward position in response to the action of the spring 27. Such port registration enables the lubricant to flow from the chamber 24 into the interior of the sleeve 26 for displacement through the outlet pipes 28 when the sleeve is forced outwardly by the action of the eccentric 30 against the resistance of the spring 27.

Keyed to the shaft 17 above the oil pump mechanism is a gear 33, the teeth of which mesh with a worm 34 fixed on a shaft 35 journaled in connection with the base section 1 and driven by the operation of an associated engine or other extraneous source of power, thereby rotating the drive shaft 17.

To reciprocate the piston members 13 and 16 in a manner to compress and explode fuel gases and resist thrust of the exploded fuels, each of the piston members is provided with a piston rod 36. The outer end of each of these rods is formed with a ball enlargement 37, which is seated in a semi-circular socket provided in the head wall of each piston, each enlargement being retained in its complementary socket by a ring nut 38 having a frusto-conical bore formed to accommodate the nut to the throw of an associated piston rod.

One of the piston rods for each bank of piston members is formed at its inner end with a threaded extension 39 which is receivable within a threaded bore provided in an eccentric strap 40, each of the latter being formed with a circular opening for the reception of an eccentric 41 keyed to the drive shaft 17, one of said eccentrics being provided for each bank of piston members. Each of the inner eccentric straps carries a surrounding outer strap 42, and each of the latter is provided with an internal opening 43 corresponding in shape to the outer configuration of the associated inner strap 40. Each of the outer straps 42 is provided circumferentially with sockets 44 in which are received for rocking movement the heads 45 of the piston rods 36, the latter being held in said sockets by means of vertical bolts or screws 46. The upper and lower ends of the bolts or screws 46 also serve to unite in connection with the eccentric structure upper and lower wear rings 47 which are mounted on the top and bottom surfaces of the eccentric straps.

Thus, as the drive shaft 17 revolves, the eccentrics 41 rotate in unison therewith, causing the straps 40 and 42 to move in unison with said eccentrics and thereby likewise imparting reciprocating movement to the piston members 13 and 16. The pattern of movement of the pivoted inner ends of the piston rods is flatly elliptic, as distinguished from the circular pattern of a conventional throw crank. The eccentrics 41 thus impart powerful compressive forces to the gaseous fuels introduced into the cylinders 12 and 14 and at the same time prevent the expansive energy produced by fuel combustion in

the cylinders from rotating the drive shaft 17. The outer ends of the cylinder section carry removable heads 48 for the upper and lower banks of cylinders 12 and 13. These heads are held in association with the cylinder section by means of the bolts or screws indicated at 49. Each head has its upper end formed to include a vertical passage 50 which communicates with the lower branched ends of a carburetor manifold 51, the latter leading to the fuel outlet of a standard carburetor employed in association with internal combustion engines. The lower end of each of the passages 50 is in open communication with the horizontal chamber 52. Slidably positioned in this chamber is the stem 53 of a fuel inlet valve 54, the tapered head of the valve 54 being normally held in engagement with the seat 55 by a coil spring 56, the latter at one end being engaged with a stationary guide 57 for the stem 53 and the other end of the spring is engaged with a seating disk 58 mounted on each of the stems 53. Each chamber 52 is rendered accessible by a removable closure nut 59. By this construction, as the piston members 13 move inwardly toward the center of the drive shaft 17, suction forces are produced in the upper cylinders 12 of a magnitude sufficient to unseat the valve 54 and thereby allow a vaporized fuel charge to be drawn into said upper cylinders.

During this operation, the diagonal passages 15 are closed by the operating positions of the lower piston members 16, said passages remaining closed as the upper piston members move outwardly in their respective cylinders to impart initial compression to the vaporized fuel charge drawn therein. When the piston members of the upper bank of cylinders reach their extreme outward positions of travel, the closed piston members 16 are then moved inwardly so that the passage or passages 15 correlated therewith is or are uncovered by the lower piston members to admit of the forced input of compressed gases into the lower cylinder or cylinders 14. Following this operation, the lower piston or pistons 16 advance in an outward direction of travel to impart additional compression to the fuel gases. When compressed by the action of the pistons, the gases are exploded by means of the spark plugs indicated at 60, or if the compression is sufficiently high by the heat of compression itself.

These highly compressed and high temperature gases are discharged from the lower cylinders 14 through horizontal discharge ports 61, one of the latter being formed in each of the manifold heads or closure plates 48. The outer end of each of the ports 61 terminates in a seat which normally receives the tapered head of a poppet-type valve 62, the stem 63 of the latter being received for sliding movement in a packed bearing 64. Each of the valves 62 is normally maintained in contact with its associated seat by a coil spring 65, the latter being confined between the inner end of an adjusting screw 66 carried by an internally threaded thimble 67 and the outer end of the stem 63. Preferably, the stem immediately to the rear of the poppet head of each valve is provided with an annular groove which registers with a vertical passage 68 provided in each of the plates or heads 48. As shown in Fig. 1, the lower ends of the passages 68 are connected by branches 69 with a trunk pipe line, shown at 70 in Fig. 5, leading to the accumulator or reservoir R for the pressure fluid. The spring loading applied to each of the valves 62 is normally sufficiently high to maintain the valves

closed, and the ports or passages 68 obstructed to fluid flow until predetermined fluid pressures are created in each of the cylinders 14, as by fuel combustion therein. Such predetermined pressures unseat the valves 62 and provide for the flow of the hot exploded gases thereby.

Another feature of the present invention resides in introducing a readily vaporizable liquid, such as water, in a controlled manner into the passage 68 in order that the liquid will be mingled with the hot exploded exhaust gases of the cylinders 14 and thereby vaporized while under pressure.

To effect such water introduction in controlled amounts into the exploded fuels, the upper end of the drive shaft 17 enters the casing 71 of a water pump, the latter being mounted on and secured to the cover plate 9 of the cylinder section. Within the casing 71, the power shaft 17 has secured thereto an eccentric 72. The periphery of this eccentric engages with antifriction ball devices 73 carried by the inner ends of slideable pump pistons 74, the latter being pressed in an inward direction by the coil springs shown at 75.

Threaded in openings formed in the casing 71 are tubular outer fittings 76 which carry water inlet and outlet connections 77 and 78, respectively. By the reciprocation of the piston 74, through the action of the shaft driven eccentric 72, water in regulated quantities is drawn into the pump cylinders 79 by way of the inlets 77 and forced from said cylinders through the outlets 78. Connected with the outlets 78 are pipes 80 each of which leads to a fitting 81 threaded into a nozzle 82 formed in connection with each of the heads or plates 48 and communicating with the passages 68 therein. Each of the nozzles 82 includes a bore 83 which is normally closed by a spring-pressed ball valve 84, the latter being normally seated but may be unseated in response to the pulsations of the water pump.

The generator unit develops energy by the explosion of vaporized fuel mixtures. In its operation, the upper bank of cylinders of the generator or compressor operate generally as a supercharger, compressing the vaporized or carburetted gases into the cylinders of the lower bank. Through the use of the eccentric drives for the piston members of these cylinders, it is possible to admit compressed fuel charges from the upper bank of cylinders into those of the lower bank without the use of valves.

When a compressed charge of gas has been admitted into one of the lower cylinders, the piston in this cylinder moves outwardly, closing its associated diagonal intake passage and compressing further the already compressed fuel gas delivered thereto from the upper cylinder. When the piston member in any one of the lower cylinders has traveled approximately one-half of its complete stroke, the dually compressed gas charge is ignited by the action of the spark plug 60, or by fuel compression. The resultant increase of pressure created by the fuel explosion is caused to escape into the storage area provided by the reservoir or accumulator R, positive operation in this regard being effected through the completion of the stroke of the lower piston member in an outward direction. The spring pressure on the balanced exhaust valve 62 is adjusted to retain the initial compression of the fuel charge plus the added compression prior to fuel combustion. Water is then introduced into the exhaust line through the passage 68 and due to the high temperature of the exhausting gases

and the regulated amounts of water so introduced, the water will flash instantly into high pressure superheated steam. The pipe line 70 leading to the accumulator and the accumulator itself may have their outer walls provided with thermal insulation or lagging to minimize heat losses. Also, the line 70 may be provided with a check valve 85 providing for fluid flow therethrough in but one direction, namely, toward the accumulator. The drive shaft 11 may be formed with an axial bore 86 which communicates with the oil pump 25, so that a lubricant advanced by the oil pump may be delivered to said bore under pressure and thence through ports or passages to the plain bearings provided at 21, 22 and 23. Also, a portion of the oil is delivered to the eccentric employed in operating the water pump indicated generally at 71. The upper end of the shaft 17 drives the rotor, not shown, of an ignition commutator 90, the latter being employed in supplying current under ignition potential to the spark plug 60 by way of the conductors indicated at 91. It will be understood that fluid pressure admitted into the motor M drives the shaft 93, and this shaft is coupled to the shaft 35 of the compressor and combustion unit A. A starting motor 92 of any conventional type may be employed to impart initial rotation to the shaft 35 at the beginning of a cycle of operation.

While I have described my improved generator as being particularly adapted for the formation of combustion products, it will be understood that the same may be employed in other capacities, such as that of a fluid pump or compressor. This can be done by the mere omission of the ignition system and fuel carburetor.

I claim:

1. In a power-developing system, a generator for the evolution of an elastic working fluid under pressure, said generator embodying a case formed with a plurality of cylinders arranged in radial order, a shaft rotatable axially of said case, pistons mounted for sliding movement in said cylinders, an eccentric fixed to said shaft for rotation therewith, strap means surrounding said eccentric, pistons slidable in said cylinders, connecting rods uniting said pistons with said strap means to impart sliding movement to said pistons when said shaft is rotated, means for introducing explosive gaseous fuels into said cylinders for compression and ignition, movement of said pistons in response to the expansive energy of the exploded fuel in said cylinders being resisted by said shaft-driven eccentric means, restricted outlet means formed in connection with said cylinders and through which the highly heated gaseous products of combustion are forcibly expelled from said cylinders, and spring loaded valve means normally closing the passage means to confine the gaseous products of combustion in said cylinders until said products attain predetermined pressures upon combustion thereof.

2. A power generator comprising: a case having formed therein adjacent banks of radially disposed compression and combustion cylinders, the combustion cylinders being substantially smaller in diameter than the compression cylinders, a centrally journaled operating shaft rotatably mounted in said case, pistons slidable in said cylinders, connecting means joining said shaft and pistons for effecting reciprocation of the latter in said cylinders upon rotation of said shaft, means operative upon movement of the pistons in one direction in the compressing cylin-

ders to draw therein vaporized fuel mixtures, means operative upon movement of said last-named pistons in an opposite direction to compress at least partially the fuel mixtures in said compression cylinders, port means for transferring said partially compressed fuel mixtures from the compression cylinders to the combustion cylinders to increase the compression of said fuel mixtures by piston action in said last-named cylinders, ignition means for exploding the gases compressed in said combustion cylinders, passage means leading exploded fuel gases from the combustion cylinders, and valve means situated in said last-named passage means and operative to maintain fuel gases in said combustion cylinders during final compression thereof until said gases attain a predetermined pressure following their combustion.

3. In a power-developing system, a generating unit for the evolution of an elastic working fluid, said unit embodying a case having formed therein adjacent banks of radially disposed fuel-compressing and combustion cylinders, the fuel compressing cylinders possessing a substantially greater diameter than that of the combustion cylinders, a centrally journaled operating shaft rotatably mounted in said case, pistons slidable in said compressing cylinders and conforming with the diameters thereof, thrust-resisting connecting means joining said shaft with said pistons for effecting reciprocation of the latter in said cylinders upon rotation of said shaft, means operative upon movement of the pistons in said fuel-compressing cylinders in one direction to draw therein a vaporized fuel mixture, means operative upon movement of said last-named pistons in an opposite direction to compress the fuel mixtures admitted into said compressing cylinders, port means for transferring said compressed fuel mixtures from the compressing cylinders to said combustion cylinders for additional compression and ignition, ignition means for exploding the compressed fuel gas in said combustion cylinders, passage means leading exploded fuel gases from the combustion cylinders, and valve means associated with said passage means for maintaining compressed fuel gases in said combustion cylinders until said gases attain a predetermined pressure and are exploded.

4. A generator for the evolution of an elastic motive fluid, comprising: a casing having formed therein adjacent banks of radially disposed fuel-compressing and burning cylinders, the fuel-compressing cylinders possessing a substantially greater diameter than the fuel-burning cylinders, a centrally operating shaft rotatably supported in said casing, pistons slidable in said fuel compressing and burning cylinders, eccentrics mounted on said shaft, strap means surrounding said eccentrics and in which the eccentrics are rotatable, connecting rods having their inner ends pivotally united with said strap means and their outer ends with said pistons, means operative upon movement of the pistons in said fuel-compressing cylinders in one direction to draw therein a vaporized fuel mixture, means operative upon movement of said last-named pistons in an opposite direction to compress the fuel mixture, port means for transferring said fuel mixture from said compressing cylinders to said fuel-burning cylinders, ignition means for exploding gaseous fuel mixtures in said burning cylinders, passage means leading burning fuel gases from the burning cylinders, and normally closed valve means cooperative with said passage means for main-

taining said fuel gases in said burning cylinders until said gases attain a predetermined pressure and are exploded by said ignition means.

5. A generator as specified in claim 4 and wherein the shaft thereof is driven by an extraneous source of power through worm gearing.

6. A motive fluid generator, as specified in claim 4, and wherein the port means employed in transferring compressed fuel mixtures from the primary compressing to the fuel-burning cylinders communicates with one end of each of the compression cylinders and with the fuel-burning cylinders at positions intermediate of the length of the latter, whereby to cause the pistons of the burning cylinders to further increase the compression of said fuel mixtures before combustion thereof takes place in said burning cylinders.
